UNITED STATES PATENT OFFICE.

WALTER MARTIN COPELAND, OF CAMBRIDGE, MASSACHUSETTS.

REGISTER.

Application filed November 12, 1926. Serial No. 148,048.

This invention relates to an improved register of the type which is commonly used in telephone systems for registering the number of calls originating on the line with which it is connected.

In a register of this type, the counting wheels are actuated by a ratchet and pawl operatively connected to a pivoted member, which is normally spring held against a back stop, and which is provided with an armature adapted to be moved in opposition to the spring by an electro magnet whenever the latter is energized by the closing of its circuit. Under actual service conditions in the register as heretofore constructed, the dampness, dirt and gases in the air frequently cause the points of contact between the back stop and pivoted member to become gummy or sticky, and as a result the magnet fails to actuate the pawl and the device fails to register, thus causing a considerable loss in revenue to the telephone company.

With the above facts in mind, the principal object of the invention is to provide an improved construction, whereby such a gummy or sticky condition is to a large extent prevented, and whatever stickiness does occur will not prevent the actuation of the register.

A further object of the invention is to construct the register so that the condition of the points of contact may be clearly observed at any time.

With the above and other objects in view, the invention comprises certain details of construction and combinations of elements, the advantages of which will be more fully explained in connection with the accompanying drawing illustrating the invention in its preferred form.

40 In the drawing:

Figure 1 is a side elevation of a register constructed in accordance with the invention.

Figure 2 is a sectional view taken on the line 2—2 of Figure 1.

45 Figure 3 is a sectional view taken on the line 3—3 of Figure 1.

The invention is shown in connection with a telephone call register comprising an electro magnet 5, having a core 6 and mounted in a housing 7. The housing projects beyond the magnet where the two sides are connected by a pivot pin 8, on which an armature 9 is mounted. Secured to the projecting sides of the housing is a cap piece 10, within which a counter 11 is mounted. The counter is adapt-

ed to be advanced through the medium of a ratchet wheel 12 secured to one end thereof, and held against backward movement by a gravity pawl 13, mounted on a pivot pin 14 extending from side to side of the cap piece. 80 The ratchet wheel 12 is adapted to be advanced by means of a pawl 15, which is pivotally mounted on a pin 16, secured to the armature 9.

The armature is normally held in its rearward position by a coil spring 18, which connects the same to a hook 19, mounted within the cap piece 10. When the electromagnet 5 is energized, it draws the armature forwardly into contact with the core 6, and in opposition to the tension of the spring 18. When the armature is in its rearward position, the rear edges of its side pieces 17 rest against a back stop, which comprises a pin 20 extending across the end of the housing 7. In accordance with the invention, this pin 20 is surrounded by a sleeve 21 of fiber, or similar material. The internal diameter of the sleeve 21 is somewhat greater than the diameter of the pin 20, so that the sleeve is held quite loosely 80 and may rotate freely thereon, as well as having a limited movement transversely of the pin.

Under service conditions, as above explained, in the absence of the sleeve 21, the pin 20 frequently becomes dirty and sticky, so that the rear edges of the side pieces 17 become stuck, and the armature fails to respond to the attraction of the magnet when the latter is energized. This sticking may perhaps 90 be somewhat increased by the slight wedging effect due to the position of the axis of rotation of the armature with respect to the back stop, and also to the slight residual magnetic effect due to the core of the magnet completing its residual magnetic circuit through the armature. This difficulty is completely overcome by the use of the sleeve 21. This sleeve has a roller action, so that in the operation of the armature it will easily roll out of any wedged position. This slight movement will also result in always presenting a new point of contact on the sleeve, and will obviate the dirty or gummy condition on the back stop. In case there is some adherence between the 95 edges of the side pieces 17 and the back stop, the loose mounting of the sleeve 21 permits the latter to move transversely with the armature to a certain extent, and the momentum thus gained by the armature will enable 100 105 110

the latter to easily overcome any adherence which might possibly be set up between the side pieces 17 and the back stop.

In order that the condition of the contact points between the side pieces 17 and the sleeve 21 may be readily observed, a notch 22 may be cut in the armature between the spring 18 and the side piece 17 at the upper end of the armature.

10 It will be understood that the circuit through the electromagnet 5 is closed by a meter key, which is depressed by the operator when a call goes through. The present invention insures the operation of the register 15 every time that the meter key is depressed. It thus insures the telephone company against loss, due to any failure which might otherwise be caused by a dirty or sticky condition within the register.

20 While I have shown and described in detail the preferred form of the invention, it is to be understood that various modifications may be made in the arrangement of the various mechanism, or in the material used with-

out sacrificing any of the essential features 25 of the invention as expressed in the claims.

What is claimed is:

1. An electromagnetic actuating device for registers and the like comprising in combination a back stop, an armature normally held 30 against the back stop, and an electromagnet operable when energized to move the armature forwardly away from the back stop, said back stop comprising a pin and a sleeve of insulating material loosely mounted thereon. 35

2. An electromagnetic actuating device comprising in combination, a pivotally mounted armature cooperating therewith, and a back stop against which the armature rests when the magnet is not energized, said back stop comprising a relatively stationary pin and a sleeve thereon, the internal diameter of the sleeve being greater than the diameter of the pin, so that the sleeve may move circumferentially or transversely of the pin. 40

45 In testimony, that I claim the foregoing as my own, I have hereto affixed my signature.

WALTER MARTIN COPELAND.
